UNITED STATES PATENT OFFICE.

HOWARD H. TALBOT, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

COUNTERBALANCE.

Application filed August 16, 1923. Serial No. 657,697.

This invention relates to counterbalances, and is particularly useful for counterbalancing the moving head of a metal working machine, as a shear, a punch, or the like.

5 In apparatus of this character, it is desirable to apply a substantially constant counter-force to the moving part, as is well known, and this has ordinarily been done by a counter-weight in one form or another. I utilize 10 means exerting a varying counter-force, as for example, a spring, and utilize such varying counter-force in an inversely varying amount. This may be done by providing 15 an arm through which the counter-force is exerted and so designing the arm that the effective length varies with the movement of the apparatus which is to be balanced. I am thus enabled to utilize a relatively small 20 spring as contrasted with the ordinary system of counterweights and levers and the entire counterbalance may be confined to a very small space while achieving the desired results in a perfectly satisfactory manner. A helical spring is preferably employed.

25 I further provide for connecting an arm to each end of the helical spring and connecting each of these arms to the apparatus to be counterbalanced, both arms being moved simultaneously. In this manner, I 30 am enabled to materially reduce the space occupied by the counterbalance since each of the arms need only to be moved one-half the distance which would be necessary if one arm alone were employed. This construction also materially simplifies the 35 design.

In the accompanying drawings illustrating the present preferred embodiment of my invention:

40 Figures 1 and 2 are diagrammatic views illustrative of my invention;

Figure 3 is a top plan view of a counterbalance embodying the invention; and

45 Figure 4 is a central vertical section, partly in elevation, of the apparatus shown in Figure 3.

Referring to the diagrams of Figures 1 and 2, there is illustrated a pair of bell crank levers L and L' pivoted at points p and p' respectively. The lower arms l and l' of the bell cranks carry the weight W which is to be counterbalanced. The upper arms l² and l³ carry a compression spring S and are urged apart thereby. It will be seen that the effec-

tive length of the upper lever arms l² and l³ 55 is the perpendicular distance r from the pivot points to the axis of the spring S, while the effective length of the lower lever arms l and l' is expressed by the distance R.

Since the apparatus is symmetrical, one 60 side alone may be considered, and for this size the length of the spring S when free and unloaded may be expressed as S' and the original compression as C. If the weight W is properly counterbalanced, or rather one-half W, since only one side of the counterbalance is being considered, the equation is 65 $1/2WR = kCr$, where k is the scale of the spring.

Referring to Figure 2, which shows the 70 load W in lowest position, it will be seen that the compression of the spring is now C' and its effective arm is reduced to r' while the load, one-half W, is still acting at the distance R. Since the spring load has increased during the downward movement, a greater spreading force is exerted between the arms l² and l³, but the mechanical advantage of the lever considered as a whole has changed, with the result that the counter-force available to return the moving parts to original position remains substantially 75 constant.

Referring to the embodiment of the invention illustrated in Figures 3 and 4, there 80 is shown a base plate 2 carried by guides 3 of a metal working machine having a vertically reciprocable head 4. Rods 5 connect the head 4 to oppositely disposed levers 6 keyed to a pair of parallel shafts 7. The 85 shafts 7 are carried in bearing brackets 8 secured to the plate 2 and each has a pair of inclined levers 9 keyed thereto. The levers 9 are connected to a pair of spring plates 10 by take-up links 11 provided with nuts 12 for varying the original distance between the 90 spring plates 10. A rod 13 runs through the spring plates 10 and carries a central spring plate 14, on either side of which are placed helical compression springs 15. A cover 16 100 may be placed over the entire counterbalance.

As the head 4 moves downwardly, the springs 15 are compressed and exert a varying counter-force, but the effective length of the arms 9 changes on account of the varying 105 inclination thereof and a substantially constant counter-moment is available for returning the head 4 to its original position after

the downward stroke. It will be understood that the head 4 is provided with stops (not shown). While it is desirable that the variation in effective length of the arms be in substantially inverse ratio to the variation in the spring force, the effective length may merely vary in an inverse manner and achieve many advantages of the invention.

I provide a counterbalance utilizing means 10 exerting a varying counter-force by providing means for utilizing the counter-force in an inversely varying amount. The entire apparatus is simple and rugged, is far more sightly than the usual counterweights employed, and is highly advantageous in comparison therewith since it is self-contained and, therefore, absolutely safe, while the heavy apparatus present in the ordinary form of counterweight is done away with 15 and numerous inertia forces thereby eliminated.

It will be understood that the apparatus need not be designed to exert a substantially constant counter-force, as certain variations 20 in the counter-force may be desirable in certain types of apparatus and this may be readily provided. It will be further understood that the variation in the proportion of the spring force utilized may be secured by other 25 means than that illustrated, as, for example, by translation cams; for, while I have shown the preferred form of my invention, it is not limited thereto, but may be otherwise embodied within the scope of the following 30 claims.

I claim:

1. A counterbalance including an arm and a connection thereon to the object to be counterbalanced, whereby a load moment is set 40 up, an arm and a spring connected thereto, the arms being adapted to vary in effective length, whereby the counter-moment is main-

tained substantially equal to the load moment.

2. A counterbalance including an arm and a connection thereon to the object to be counterbalanced, whereby a load moment is set 45 up, an arm and a spring under initial load connected thereto, the arms being adapted to vary in effective length, whereby the counter-moment is maintained substantially equal 50 to the load moment.

3. A counterbalance including an arm and a connection thereon to the object to be counterbalanced, whereby a load moment is set 55 up, an arm and a spring under initial load connected thereto, the arms being adapted to vary in effective length, whereby the counter-moment is maintained substantially equal to the load moment, and means for adjusting 60 the initial load.

4. A counterbalance including a pair of arms and connections thereon to the object to be counterbalanced, whereby load moments are set up, a pair of arms connected one to each of the first pair and connected by means 65 tending to supply a varying counter-force as the arms are moved, the arms being adapted to vary in effective length, whereby the counter-moment is maintained substantially 70 equal to the load moment.

5. A counterbalance for the moving head of a metal working machine, comprising a head to be counterbalanced, a counterbalancing spring, and a bell crank connecting the 75 spring and the head, one arm of said bell crank being adapted to maintain a substantially constant length and the other arm being adapted to provide an effective length which varies inversely with the power of the spring.

In testimony whereof I have hereunto set my hand.

HOWARD H. TALBOT.
